SUPPORT FOR SUSPENDED FILES

BACKGROUND OF THE INVENTION

1. Field of the Invention

The invention relates to filing devices and particularly to a support frame for suspended files containing sheets of papers at least a portion of which are removable and interchangeable, adapted to be preserved in file drawers or the like, permitting inspection of sheets of paper without withdrawing them from the containing receptacle.

2. Description of the Prior Art

One typical method of storing papers for reference utilizes a scheme of containing the papers in file folders which are suspended vertically. The upper edges of the folders have strengthening or stiffening means which typically project laterally at each end and are supported on horizontally extending support rails. When the file folders are stored in drawers of a filing cabinet, for example, the rails are conventionally part of a frame including vertical posts which rest on the bottom of the drawer and are interconnected by cross bars. Such frame assemblies may be inserted readily into existing plain drawers which may thus be converted to contain suspended filing systems. The present invention is concerned with a supporting frame of the above type.

Such frame assemblies can be arranged so that they will be easily assembled by the user without special tools from a small number of components which may be packed into small space for storage and shipping.

The frame assemblies readily adapt themselves to a great variety of drawer types and are of such a nature that the user can assemble the frame with associated rails at desired spacings.

Constructions of the prior art which are directed toward similar objectives as the present invention are illustrated and described in U.S. Pat. No. 3,295,697, entitled "LOCK LEVER SUSPENSION FILE SUPPORT", E. D. Patterson. The constructions disclosed therein are considerably more complex than the instant structure and are therefore more costly to manufacture and cumbersome to utilize.

SUMMARY

The object and advantages of the present invention may typically be achieved by a support frame assembly having a pair of vertically extending corner posts interconnected by a transverse cross bar at each end of the support frame and rails between the ends of the frame, means for connecting the rail, cross bar, and corner post at each corner of the frame, said means comprising an integral portion of the cross bar consisting of a horizontally extending portion and terminal section having a rail engaging portion; an integral upper terminal portion on the corner post having a rail engaging portion cooperating with the rail engaging portion of the terminal section of the cross bar; linkage means interconnecting the terminal sections of the cross bar and the corner post; and means disposed between the undersurface of the cross bar and the uppersurface of the terminal portion of the corner post for effecting relative movement of the rail engaging portion of the cross bar and the rail engaging portion of the corner post to snugly engage a portion of the associated rail.

BRIEF DESCRIPTION OF THE DRAWINGS

Other objects and advantages of the invention will become readily apparent to one skilled in the art from reading the following detailed description of the invention, when considered in the light of the accompanying drawings, in which:

FIG. 1 is a perspective view of a support frame for suspended files incorporating the features of the invention;

FIG. 2 is an enlarged fragmentary elevational view of one corner of the support frame illustrated in FIG. 1, showing the terminal portions of the cross bar and the corner post separated to accommodate reception of an associated rail member;

FIG. 3 is a top plan view of the apparatus illustrated in FIG. 2;

FIG. 4 is an enlarged fragmentary elevational view of the apparatus illustrated in FIG. 2 subsequent to the movement of the locking arm into a locked position;

FIG. 5 is a fragmentary top view of a modified form of the structure illustrated in FIGS. 1, 2, 3, and 4 preparatory to receiving an associated rail member;

FIG. 6 is an elevational view of the structure illustrated in FIG. 5; and

FIG. 7 is an elevational view of the structure illustrated in FIGS. 5 and 6 subsequent to the movement of the locking arm to a locked position.

DESCRIPTION OF THE PREFERRED EMBODIMENTS

15 Referring to FIGS. 1, 2, 3, and 4, there is illustrated a support frame structure useful for supporting suspended files wherein there are typically provided two end frame members, spaced apart, one adopted to fit in the front of a drawer and the other in the back portion of the drawer. These members 20 comprise generally vertically extending arms connected at the bottom by a horizontally extending section which is adapted to rest on the bottom of the drawer, and having at the upper end a corner post including an outwardly extending rail engaging portion. The upper ends or corner posts of these arms are connected by a cross bar extending therebetween and to each of the outwardly extending portions. The cross bar terminates in rail engaging portions. The ends of the rail members, received by the rail engaging portions of the corner posts and cross bars, are secured thereby by the action of a locking arm.

30 More specifically, the support frame of the invention comprises two horizontally extending rail members 10, and at each end, a frame comprising a cross bar 12 and two vertically extending corner posts 14, the lower ends of which are interconnected by a bottom horizontally extending bar 16. Typically, 35 excellent results have been found to occur when the aforementioned elements are fabricated from strip metal of uniform section with smooth edges throughout. The metal material used for fabricating the end frames should preferably have spring qualities, as will become manifest in the following 40 description.

Each of the corner posts 14 has the terminal upper ends thereof formed with a horizontally extending section 18 and a substantially U-shaped rail engaging terminal portion 20. The cross bars 12 terminate in an inverted substantially U-shaped 45 rail engaging terminal section 22. The terminal portion 20 of the corner post 14 and the terminal portion 22 of the cross bar 12 are in suitable superposed cooperating relation to adequately engage the rail member 10 as will be described in greater detail hereinafter.

50 The cross bar 12 and the horizontally extending section 18 of the corner posts 14 are interconnected by a pivot fastener 24, for example, having an upper head 26 and a lower head 28. A locking arm 30 is interdigitated between the lower surface of the cross bar 12 and the upper surface of the horizontally extending section 18 of the corner post 14. It will be obvious that suitable apertures are formed in the cross bar, the horizontally extending section 18 of the corner post, and the locking arm 30 to suitably receive the fastener 24 prior to the 55 placement of the heads 26 and 28.

60 The locking arm 30 is provided with a projection 32 extending upwardly from the uppersurface thereof, and a projection 34 depending downwardly from the lower surface thereof. The lower surface of the cross bar 12 is provided with a recess or hole 36 adapted to receive the projection 32, while the upper surfaces of the horizontally extending section 18 of the corner post 14 is provided with a recess or hole 38 adapted to receive the projection 34.

65 It will be noted that when the locking arm 30 is in the position illustrated in FIGS. 1, 2, and 3, the projections 32 and 34 are effective to spring apart the rail engaging sections 20 and 22 of the corner post 14 and the cross bar 12, respectively, to enable the rail member 10 to be readily received therebetween. The rail member 10 is inserted between the rail 70 engaging sections 20 and 22, and thence the locking arm 30 is

swung to the position illustrated in FIG. 4, where the longitudinal axis thereof is in general alignment with the cross bar 12 and the horizontally extending section 18. In the above position, the projections 32 and 34 align with and seat within their respective recesses or holes 36 and 38, which permit the rail engaging sections 20 and 22 to snap toward each other to a closed position, as illustrated in FIG. 4, to thereby firmly engage the rail member 10 in a secure, locked position.

Manifestly, it will be appreciated that to unlock the assembly, the locking arm 30 is manually swung to the position illustrated in FIGS. 1, 2, and 3, whereupon the rail engaging sections 20 and 22 are sprung to an open position, permitting withdrawal of the associated rail member 10.

While the embodiment of the invention illustrated in FIGS. 1, 2, 3, and 4 incorporate a pair of cooperating projections 32 and 34 on the locking arm 30, it will be appreciated by one skilled in the art that a single projection could be utilized to cam or spring the rail engaging sections 20 and 22 apart to receive the associated rail member 10.

FIGS. 5, 6, and 7 illustrate a modified version of the structure illustrated in FIGS. 1, 2, 3, and 4, wherein there is an assembly including a corner post 114 formed with a horizontally extending section 118 which terminates in a downwardly depending rail engaging portion 120. The associated cross bar 112 terminates in an upstanding rail engaging portion 122. The terminal rail engaging portion 120 of the corner post 114 and the terminal rail engaging portion 122 of the cross bar 112 are in suitable superposed cooperating relation to adequately engage the associated rail member 110, as will be explained in greater detail hereinafter.

The cross bar 112 and the horizontally extending section 118 of the corner post 114 are interconnected by a rivet type fastener 124, for example, having an upper head 126 and a lower head 128. A locking arm 130 is interdigitated between the lower surface of the cross bar 112 and the upper surface of the horizontally extending portion 118 of the corner post 114. Obviously, suitable apertures are formed in the cross bar 112, the horizontally extending section 118 of the corner post 114, and the locking arm 130 to suitably receive the shank portion of the fastener 124 prior to the placement of the heads 126 or 128.

The locking arm 130 is provided with a pair of cooperating cam surfaces 132 and 134 struck from the upper and lower surfaces of the locking arm 130, respectively. Accordingly, when the locking arm 130 is in the position illustrated in FIGS. 5 and 6, the cam surfaces 132 and 134 are ineffective and thereby allow the terminal portion 122 of the cross bar 112 and the terminal portion 120 of the horizontally extending portion 118 of the corner post 114 to remain in their normal condition wherein the rail engaging portions are able to readily receive the rail member 110. While it has been found desirable to form the end frames from flat strip metal stock of uniform section with smooth edges throughout, the rail members 110 are preferably formed of a thinner material having a generally C-shaped cross sectional configuration. Further, as will be manifest, the oppositely extending terminal portions 120 and 122 engage within the channels formed on the upper and lower inner surfaces of the rail member 110.

When the associated rail member 110 is to be assembled or interconnected with the end frame structure described above, the rail member 110 is moved into position such that the downwardly depending rail engaging portion 120 of the corner post 114, and the upwardly extending terminal rail engaging portion 122 of the cross bar 112 are received within the interior of the channel formed by the cross sectional configuration of the rail member 110. Once the end of the rail member 110 is thus assembled or positioned, a locking arm 130 is pivoted or swung to the position illustrated in FIG. 7. It will be noted upon examination of FIGS. 5, 6, and 7 that the upper and lower surfaces of the locking arm 130 are provided with an inclined plane camming surface 132 and 134, respec-

tively, such that as the locking arm is swung to the position illustrated in FIG. 7, the camming surfaces 132 and 134 act to cam the rail engaging portions 120 and 122 away from one another and into firm frictional engagement with the interior channels formed by the rail member 110. As the locking arm 130 approaches alignment with the cross bar 112 and the horizontally extending section 118, the entire camming surfaces 132 and 134 are positioned over the planar surfaces with which they are cooperating and, in effect, lock the structure in an assembled form.

While the embodiment illustrated in FIGS. 5, 6, and 7 illustrate a pair of camming surfaces 132 and 134, it will be appreciated that a single camming surface could be utilized to effect the desired separation of the terminal rail engaging portions 120 and 122 to effect the desired locking relation.

Further, it should be pointed out that in certain embodiments it may be desirable to construct the locking arm 130 to have a length from the shank of the fastener 124 slightly greater than the distance of the outer surface of the rail engaging elements 120 and 122 from the shank portion of the fastener 124 such that in a fully locked position, the outermost end of the locking arm 130 is in contact with the inner surface of the rail member 110 to provide additional frictional engagement therebetween.

In accordance with the provisions of the patent statutes, we have explained the principle and mode of operation of our invention and have illustrated and described what we now consider to represent its best embodiment. However, we desire to have it understood that the invention may be practiced otherwise than as specifically illustrated and described without departing from its spirit or scope.

Having described the embodiments of the invention we claim:

1. A support frame assembly having a pair of vertically extending corner posts interconnected by a transverse cross bar at each end of the support frame and rails extending between the ends of the frames, means for connecting the rail, cross bar, and corner post at each corner of the frame, said means comprising:

an integral terminal portion of the cross bar consisting of a horizontally extending portion and terminal section having a rail engaging portion;

an integral upper terminal portion of the corner post having a rail engaging portion cooperating with the rail engaging portion of the terminal section of the cross bar; means disposed between the facing surfaces of the cross bar and the corner post for effecting relative movement of the rail engaging portion of the cross bar and the rail engaging portion of the corner post to snugly engage a portion of the associated rail; and linkage means interconnecting said means and the terminal portions of the cross bar and the corner post to permit relative movement between said means and the cross bar and the corner post.

2. The invention defined in claim 1 wherein said means includes a pivotally mounted arm.

3. The invention defined in claim 2 wherein said pivotally mounted arm contains at least one camming surface.

4. The invention defined in claim 2 wherein said pivotally mounted arm contains a first camming surface projecting upwardly from said arm and a second camming surface depending downwardly from said arm.

5. The invention defined in claim 3 including a cavity formed on the under surface of the cross bar for reception of said camming surface when said arm is in general alignment with the cross bar.

6. The invention defined in claim 4 wherein the cross bar and the corner post are provided with recesses for receiving respective ones of said camming surfaces when said arm is in general alignment with the cross bar.
